DOBBY FOR WEAVING

Rudolf Rossmann, Gauting, near Munich, Germany, assignor to Tefag Textil-Finanz A.-G., Zurich, Switzerland

Application May 27, 1933, Serial No. 673,224
In Germany June 2, 1932

4 Claims. (Cl. 139—66)

This invention relates to dobbies for weaving and is particularly, though not exclusively, applicable to those employing gripping or "nipper" shuttles.

For the purpose of forming the necessary sheds to produce a desired pattern in the manufactured fabric a loom has been furnished with a number of shafts constituting heald frames each having an upper and a lower bar or stave, the healds extending between these staves with a warp thread passing through an eye incorporated in each heald. The necessary up and down or shedding movement has then been transmitted to the heald frames through cords, belts or chains from control mechanism laterally arranged on the loom or above the warp. The overall height of a loom of this type is however such as not only to necessitate undesirably high ceiled workshops but the loom itself tends to obstruct the light and thus add to the difficulties of the operator. Further, it has been necessary to reduce lubrication of the dobbies to an undesirably low value since if adequate lubrication is provided the lubricant tends to find its way on the warp and thereby spoil the manufactured fabric. Again, the drive was not transmitted from the dobbie control mechanism to the heald shafts in a rigid manner and, in some cases, not even positively, with the result that undesirable vibrations were produced in the mechanism as a whole. The present invention has for its object to overcome these difficulties.

To this end according to the present invention each heald frame is supported on a rigid bearer longitudinally extending over the whole length of the frame and lying below the shed, and shedding movement is imparted to the bearer by actuating rods positively guided to move vertically.

It is obvious that with such an arrangement the frames themselves can be made very light whereby the power and space requirements of the mechanism are considerably reduced.

Preferably each heald frame comprises light longitudinal bars or cords between which extend the healds, and rigid vertical members which extend transversely between and connect the longitudinal bars at intervals spaced apart and through which the frame is supported by the bearer. Conveniently each bearer is made hollow and is furnished internally with pins which can be engaged with or disengaged from the actuating rods by relative movement of the rods and bearer in a direction transverse to the length

of the actuating rods. Thus, for example, by moving the bearer in the direction of its length the bearer can be disengaged from the actuating rods, whereupon the heald frame and warp can be lifted off.

Movement may be transmitted to each actuating rod through a swinging link pivotally connected to the actuating rod, means being provided for swinging the links into or out of engagement with oscillating knives. Alternatively movement may be directly transmitted to each actuating rod through a bell-crank lever from card-feeler mechanism.

When the actuating rods are operated by knives cooperating with swinging links, two knives are preferably provided one on each side of a swinging link, the knives being oscillated relatively to each other with that end of the link remote from its connection to an actuating rod engaged by intermediate mechanism actuated by card-feeler mechanism. The knives are preferably oscillated about a centre which lies substantially vertically below the beating up point of the weft so that the healds more remote from the beating up point will be moved through a greater distance than the healds nearer to the beating up point, whereby the same shed angle will be obtained by each frame.

In the accompanying drawings:

Figure 1 is a sectional end elevation of a loom embodying one form of the invention,

Figure 2 illustrates, on an enlarged scale, the mechanism for transmitting movement to each heald frame,

Figures 3, 4 and 5 show on a still larger scale three different operative positions of one of the swinging links included in Figure 2,

Figure 6 is a perspective, on a larger scale than that of Figure 1, of part of a heald frame,

Figure 7 illustrates an alternative construction of apparatus for transmitting movement to each heald frame, also according to the invention,

Figures 8 and 9 show the manner in which the shed is formed in a loom embodying the invention, and

Figures 10 and 11 are diagrammatic illustrations in side elevation and sectional plan respectively of another form of knife which may be employed for imparting movement to the heald frames.

In the construction illustrated in Figures 1 to 6 inclusive the frame 1 of the loom carries on one of its longitudinal sides a let-off beam 2 from which the warp threads pass over a swing beam 4. The shed 5 is formed as hereinafter described and

the weft picked in and beaten up so as to form the fabric 6 which passes over a breast beam 7 to a take-up beam 8. The shed 5 is formed by a series of heald frames the upper bars of which are indicated at 19a, 19b, 19c and 19d, the frames being carried by bearers 10a, 10b, 10c and 10d which serve to guide the frames during their vertical up and down or shedding movements. Movement is transmitted to the frames through actuating rods 11a, 11b, 11c and 11d and swinging links 12a, 12b, 12c and 12d, the effective actuation of these links being controlled through actuating mechanism comprising bars 13a, 13b, 13c, 13d, 14a, 14b, 14c and 14d as hereinafter described. Movement is imparted to the links 12a, 12b, 12c and 12d by knives 15a and 15b which are oscillated relatively to each other by face cams 16 engaging bell crank levers 17a and 17b carrying the knives 15a and 15b respectively.

Figure 2 illustrates the manner in which movement is transmitted to each of the heald frames included in Figure 1. The heald frame comprises a series of transverse supports 18 extending between longitudinal bars or cords 19, the frame being furnished at its lower edge with a flat bearer member 10. Each heald 47 is supported at its ends (Figure 6) on the bars 19 and is furnished with an eye 48 for the passage of a warp thread. The bearer member 10 is hollow as shown and each rod 11 is provided at one end with a hook 49 adapted to engage a pin 50 arranged inside the guide member 10. Each heald frame can thus be disengaged from its actuating rods 11 by simply causing relative movement between the frame and the rods 11 in a direction transverse to the length of the rods 11.

As clearly shown in Figure 2 each link 12 is pivotally connected at its upper end to its associated actuating rod 11 and is furnished at its lower end with a tongue or spike freely movable through an aperture 20 in the bar 13. The rods 11 are positively guided in a cross-bar 21 as shown and each link 12 is provided with two recesses or forks 49' and 50' adapted to cooperate respectively with the knives 15a, 15b, the pivot 22 of which is arranged vertically below the beating up point of the weft. In this way the heald frames more remote from the beating up point, being operated by the ends of the knives 15a, 15b, are moved through a greater vertical distance than the frames nearer to the beating up point whereby the angle of the shed is maintained from the beating up point to the frame most remote therefrom and the same shed angle will be provided for every pick.

Mounted on a pivot 23 is a short lever 24 to the ends of which the bars 13 and 14 are connected, a pivot 25 carrying a similar lever 26 connecting the other ends of the bars 13 and 14. Link 14 may be omitted. Pivotally connected to the two ends respectively of the lever 26 are two latch-pieces 27 and 28, the latch-piece 27 having a downwardly directed nose 29 whilst the latch-piece 28 is furnished with an upwardly directed nose 30. Pivoted on a fixed portion 31 of the frame is a bell-crank lever one arm of which carries a finger 32 whilst the other arm 33 is furnished with a roller 34 bearing on a cam 35. A short lever 36 carries at one end a roller 37 which bears against the cam 35, the other end of the lever 36, which is pivoted at 38, being pivotally connected to a rod 39 guided in a bore in the frame member 31 and capable of engaging the latch-piece 28. The nose 40 of the rod 39 co-

operates with any suitable pattern forming mechanism (illustrated by dotted lines 43) for co-operative movement with the needle or feeler 44 guided in the frame member 31 and having eyes 45 engaged by pins 46 formed on the end of the 5 latch pieces 27 and 28. The needle or feeler 44 rises and lowers in accordance with the desired changes in the pattern.

The operation of the apparatus is as follows:—

In Figure 3 the frame to which the link 12 is connected has been moved into its uppermost position as shown, for example, by the frame 19c in Figure 1, the knife 15a engaged with the link 12 having moved upwards as shown by the arrow A in Figure 3, whilst the knife 15b has moved downwards as shown by the arrow B. The movement of the frame now begins to take place in the reverse or downward direction and, when the knives 15a and 15b arrive at the same level (Figure 4) the bar 13 is moved as hereinafter described so as to turn the link 12 in the direction of the arrow C whereby the knife 15b engages the link 12 whilst the knife 15a is simultaneously disengaged therefrom. As the link 12 is turned into the position shown in Figure 5, the knife 15a moves 25 idly upwards as shown by the arrow D whilst the link 12 and therefore the heald frame associated therewith are moved by the knife 15b downwards in the direction E until the heald frame reaches 30 its lowermost position.

As the cam 35 rotates it rocks the lever 36 about the pivot 38 so as to reciprocate the rod 39. The reciprocating movement of the rod 39 simultaneously causes the latch-piece 28 to be raised and lowered so as to raise and lower the needle 44 which cooperates with a card feeler mechanism which controls the extent of the up and down movement of needle 44. This mechanism is not shown because it is not part of the present invention. The parts are now in the positions 40 shown in Figure 2. As the cam 35 continues to rotate in the direction indicated by the arrow the rod 39 and therefore the needle 44 descends and the latch-piece 28 will move downwards until its nose 30 lies outside the path of the finger 32, the 45 nose 29 simultaneously moving downwards into the path of the finger 32. The cam 35 now moves the bell crank lever 33 in the clockwise direction as viewed in Figure 2 so that the finger 32 engages the nose 29 and moves the bar 13 so as to turn the 50 links 12 from the position indicated in Figure 3, corresponding to the uppermost position of the heald frame, to the position shown in Figure 5 corresponding to the lowermost position of the heald frame, the knives 15a, 15b cooperating with 55 the links 12 as above described.

The bell-crank lever 33 now commences to move back in the counter-clockwise direction and the cam 35 causes the needle 44 to be lifted. On the next descent of the needle 44, the nose 29 60 will again be brought into the path of the finger 32 but will not be engaged thereby so that the heald frame will not be moved sufficiently in the upward direction to form a new shed. If, on the other hand by the card feeler mechanism, not 65 shown, the needle 44 is held in lifted position, the nose 29 will be held out of the path of the finger 32 whilst the nose 30 will lie in such path whereby on the next operative movement of the finger 32 this will engage the nose 30 and move the bar 14 70 to the right, thereby moving the bar 13 to the left. In this way as the links 12 move upwards they are turned from the position shown in Figure 5 to the position shown in Figure 4 whereupon the knife 15b will become disengaged from and the 75

knife 15a engaged with the links 12. The knives 15a will then carry the links upwards to the position shown in Figure 3 thereby raising the heald frame to form a shed.

5 The relative rotation of the cam 35 and therefore reciprocation of the finger 32, and rotation of the cam 16 is such that engagement and disengagement of the knives 15a and 15b with the links 12 will always take place smoothly at the 10 central position of each link 12.

Figure 7 illustrates an alternative construction in which movement is transmitted to the actuating rods 11 through bell-crank levers pivoted on the cross-bar 21, a slot 51 in one arm of each bell 15 crank lever freely engaging a pin carried by the corresponding actuating rod 11 whilst the other arm 52 of the bell-crank lever is connected to the bar 13. Pivoted connected to one end of the bar 13 is a latch-piece 27 carrying a pivot pin 53 on 20 which is mounted a pawl 54 furnished at its opposite ends with noses 55, 56. A lever or knife 57 pivoted at 58 on a fixed part of the loom is provided at its free end with a nose 59 arranged to cooperate with the nose 55 on the pawl 54. A pin 60 carried by the knife 57 engages a cam groove 61a in a cam 61, the cam groove being simultaneously engaged by a pin 62 carried by a knife 64 pivoted at 63 and furnished at its free end with a nose 65 arranged to cooperate with the 30 nose 56 on the pawl 54. The pawl 54 carries a pin 66b which engages a slot 66a in a member 67 carrying the needle 44 and vertically movable within a fixed part 68 of the loom upon which part the free end of the latch-piece 27 can slide 35 longitudinally.

One arm of a bell-crank lever 70 pivoted on the frame 68 lies adjacent to the lower end of the member 67 whilst the other arm of the bell crank lever 70 bears against a projection 71 formed on 40 the knife 64. A spring 72 is connected at one end to the knife 64 and at its other end to a short lever 73 pivoted at 74, the upper end of the lever 73, which is thus held in engagement with the bell-crank lever 70, carrying a pawl 75 arranged to cooperate with the teeth 42 of the ratchet wheel 41. The projection 71 is thus operatively connected with the pawl 75 through one arm of the bell-crank lever 70.

The operation of the apparatus shown in Figure 50 7 is then as follows:—

Assuming that the parts are in the positions shown and that the needle 44 is immediately over an unperforated portion of the card 43, when the cam 61 rotates in the direction of the arrow the 55 knives 57 and 64 will commence to move inwards towards each other. The bell-crank lever 70 will now turn in the clockwise direction and the needle 44 will descend and will rest on the unperforated part of the card 43. The total downward movement of the member 67 will not be sufficient to rock the pawl 54 far enough to move its nose 55 out of the path of the nose 59 on the knife 57 or to move the nose 56 into the path of the nose 65 of the knife 64. As the cam 61 continues to 60 rotate the knives 57 and 64 will move further towards each other and the nose 59 engaging the nose 55 will move the bar 13 to the right and thus raise the heald frame to form a shed. When the two knives 57 and 64 are nearest together the 65 pawl 75 will have moved to engage another tooth of the ratchet wheel 41 and will be ready to effect the next forward movement of the card 43.

The knives 57 and 64 will now commence to move apart and the projection 71 will turn the bell-crank lever 70 so as to raise the needle 44

clear of the card 43, the projection 71 at the same time moving the pawl 75 to turn the ratchet wheel and advance the card by one step. The knives 57 and 64 are now in the position shown in Figure 7 and, if the needle 44 is immediately over a 5 perforation in the card 43, when the needle descends as above described it will enter the perforation. The member 67 will thus move downwards sufficiently to rock the pawl 54 so as to bring the nose 56 into the path of the nose 65 10 and to move the nose 55 out of the path of the nose 59. As the knives 57 and 64 move inwards therefore the nose 65 will engage the nose 56 so as to move the bar 13 to the left and thereby lower the heald frame to the lowermost position 15 shown.

The heald frame can be readily detached from the actuating rods 11 by moving the frame to the right as viewed in Fig. 7, so that the pins 50 move out of the slots 49. Ready access can be thus 20 had to the parts of the looms beneath the heald frame.

Figs. 8 and 9 illustrate the manner in which the shed is formed due to the operation of the heald frames as above described with reference 25 to Figs. 1 to 5, inclusive. The diagrams Figs. 8 and 9 are shown in connection with a modification of the knife mechanism designated by Fig. 10. The line constituting the edge of the knives 15 on Fig. 1 as well as 79 on Fig. 10 oscillates 30 around a pivot which is vertically below the beating-up point. For this reason, the heald frames 48, of which only the eyes 48 for letting through the warp threads are shown in Figs. 8 and 9, are raised higher the farther they are from 35 the beating-up point so that the shed angle is the same for every pick.

Figs. 10 and 11 illustrate an alternative form of a knife operating mechanism comprising a disc 78 which carries a knife 79 and which is 40 equivalent to the knives designated in Fig. 1 by numerals 15a and 15b and in Fig. 7 by numerals 59 and 65. The disc 78 is slidably and revolvably movable in guides 76 and 77 of the stationary carriers 86 and 87. A link 80 is 45 revolvably carried by pin 81 on disc 78; the other end of the link 80 is revolvably carried by pin 82 which is mounted to the stationary member having a recess 83 to accommodate link 80. As the disc 78 reciprocatingly moves within guides 76 and 50 77, the disc not only slides along the guides but, at the same time rolls therein. The movement is imparted to disc 78 by a rod 57' between the solid and dotted line positions which has a ball-shaped 55 end wobbling in a corresponding eye in hub 89 of disc 78. Link 80 is so dimensioned and pin 82 so arranged that the rolling movement of disc 78 causes knife 79 to be turned about an imaginary center 22' which lies vertically below the beating-up point of the weft threads.

It will be understood that the constructions above described are given by way of example only and that details may be modified.

A dobby according to the invention has the advantage that the overall height of the loom is 65 small so that the accessibility and visibility of the parts are facilitated whilst, in addition, the loom does not tend to obstruct the light unduly. Further, the cost of manufacture is reduced and the tendency for lubricant to fall from the dobby 70 on to the fabric is obviated since the dobby is arranged below the warp and between the take-up and let-off beams.

I claim:—

1. In a dobby for weaving, a plurality of indi- 75

- individual heald frames, a plurality of bearers individually supporting said individual heald frames, a plurality of actuating rods individually supportingly connected with each of said bearers, bell 5
5 crank levers having two arms, always one of said levers being movably connected by one arm with one of said actuating rods, longitudinal members individually movably engaging all of said bell crank levers connected by means of said actuating 10
10 rods to the same of said bearers, a pawl carried by each of said longitudinal members, a pair of knives adapted to alternately engage said pawl and move the longitudinal member by which said pawl is carried in substantially the direction of its length, an operating mechanism operatively connected to and adapted to oscillatingly move said knives, and a card feeler mechanism operatively connected to and adapted to control the movements of said operating mechanism. 15
15 2. In a dobby for weaving, a plurality of individual heald frames, a plurality of bearers individually supporting said individual heald frames, a plurality of actuating rods individually supportingly connected with each of said bearers, bell 20
20 crank levers having two arms, always one of said levers being movably connected by one arm with one of said actuating rods, longitudinal members individually movably engaging all of said bell crank levers connected by said actuating 25
25 rods to the same of said bearers, a pawl carried by each of said longitudinal members, a pair of knives adapted to alternately engage said pawl and move the longitudinal member by which it is carried in substantially the direction of its length, an operating mechanism operatively connected to and adapted to oscillatingly move said knives, and a card feeler mechanism operatively connected to and adapted to control the movements 30
30 35

of said operating mechanism, said card feeler mechanism comprising a needle-carrier having a lateral arm, and a slot in said arm, said pawl carrying a pin adapted to move within said slot and permit reciprocating movement of said pawl and the longitudinal member by which it is carried. 5

3. In a dobby for weaving having heald frames each comprising flexible longitudinal members, healds extending between said longitudinal members and rigid upright members interspersed between said healds and extending transversely between and connecting and supporting said longitudinal members, a longitudinal bearer for each heald frame located beneath the shed and rigidly connected to and supporting said upright members, said bearer being hollow and having internally located pins, and actuating rods extending into the inside of said bearer and being removably connected with said pins. 20

4. In a dobby for weaving having heald frames each comprising flexible longitudinal members, healds extending between said longitudinal members and rigid upright members interspersed between said healds and extending transversely between and connecting and supporting said longitudinal members, a longitudinal bearer for each heald frame located beneath the shed and rigidly connected to and supporting said upright members, said bearer being hollow and having internally located pins, and actuating rods extending into the inside of said bearer, said rods having hooks which engage said pins and are adapted to disengage said pins upon movement of said bearer in a direction transverse to the longitudinal extension of said rods. 25 30 35

RUDOLF ROSSMANN.
